FIG. 1.

FIG. 3.

FIG. 2.

INVENTOR
Lee Bruce Moore

BY his ATTORNEY.

UNITED STATES PATENT OFFICE

2,278,209

KNITTING BAG FRAME

Lee Bruce Moore, New York, N. Y.

Application May 20, 1941, Serial No. 394,246

2 Claims. (Cl. 150—34)

This invention relates to improvements in the construction of a knitting bag and has reference particularly to a bag of this character, having a hinged frame, which carries a removable yarn spool and which is provided with a slot in the closed position of the frame to accommodate the passage of the yarn being unwound from the spool as the yarn is used in the knitting process.

My invention has for its object to provide a novel construction for a knitting bag supporting therein a spool for the yarn, and means embodied in the spool to rotate the latter to wind the yarn upon the spool.

A further object of the invention is to provide hinged frame sections, which are grooved along their meeting surfaces, so as to form a slot in the closed position of the sections for the passage of the yarn from the spool inside the bag to the work outside the bag.

I accomplish these objects by means of a construction, one embodiment of which is described in the specification, set forth in the appended claims and illustratively exemplified in the accompanying drawing in which:

Figure 1 is a perspective view of my improved knitting bag in closed position;

Figure 2 is a substantially transverse sectional view taken on lines 2—2 of Figure 1;

Figure 3 is an elevational view of the bag in its extreme open position;

Figure 4 is an elevational view of one end of the spool showing the telescopic crank in its collapsed position.

Referring to the drawing, 10 denotes the bag body which is constructed of cloth, leather or any other suitable material, and which is provided with hinged closure frames 11. The frames 11 are inverted rigid U-shaped members of wood, metal or plastic material having suitable hinge connections 12 connecting the ends of the side arms together in the usual manner. The inner face of the cross bar or top of each frame 11 is recessed from points short of opposite ends thereof so as to form a slot 13 between the frames when the latter are closed, as in Figures 1 and 2. Beyond the ends of the recess in one frame 11 there are hooks 14, which are hinged at their inner ends to the outside of the frame, and which are provided with angular tongues 15 at their free ends to fit over the top of the two frames and embrace the outer face of the other frame section 11.

One of the frame sections 11 is provided with grooves 16 disposed transversely in the inside

faces of the side arms, the grooves being coaxial to accommodate axles 17 of a yarn spool 18, as illustrated in Figures 2 to 4. Slidably mounted in longitudinal grooves 19 in the side arms of the frame are plates 20 which, in closed position, project over the axles 17 to hold them in their grooves 16, see Figure 3.

The spool 18 is substantially the length of the bag opening between the side arms of the frames 11 and comprises a cylindrical core 21 terminating at its ends in flanges 22 from which the axles 17 project.

One of the axles 17 comprises a tubular member 23 enclosing an extensible crank handle comprising an inner rod 24 capable of being moved only longitudinally of the tubular member 23 and being provided with a yoke 25 at its outer end. Pivotedly connected at one end in the yoke 24 is a link 26, which telescopes into the tubular member 23, as shown in Figure 4, when the handle is not in use, and which is pivotally connected at its outer end to a grip or handle 27. In the projected position of the crank handle, the yoke 24 is drawn to a point beyond the end of the member 23 and the link 26 is swung to a position at right angles to the rod 24 and the grip 27 is swung to a position parallel to the axis of the spool, so as to cause the latter to be revolved by turning the crank. When not in use, the rod 24 and link 26 are telescoped into the tubular member 23 and the grip 27 simply hangs from the end of the link along the ends of the side arm of the frame, as shown in Figure 1.

In use the bag is adapted to contain not only the spool of yarn A but the work and needles as well. When the work is removed from the bag, the yarn from the spool 18 passes outwardly through the slot 13 after closing the frames 11.

In order to refill the spool 13 with yarn A, the bag may be placed in the extreme open position, shown in Figure 2, with the frame section 11 having the hooks 14 resting upon a table surface and the frame section 11 carrying the spool overhanging the edge of the table. The crank handle is then placed in operating position and manipulated to revolve the spool 18 and wind thereon a supply of yarn. The handle is then collapsed and the frames 11 closed about the stand of yarn projecting through the slot 13. If necessary, the bag may contain a number of spools of yarn, in which case it is only required to operate the plates 20 to free the empty spool and allow a full spool to be substituted therefor.

Having now described my invention and the

manner in which the same is operated, what I claim and desire to secure by Letters Patent is:

1. A knitting bag of the character described, comprising a flexible bag portion open at the top thereof, a closure frame for the open end of said bag, comprising hinged sections having recesses in the meeting faces thereof to form a slot opening into the bag when the frame is closed, one of said sections being provided in its meeting face with aligned grooves having plates to close there-

over, and a yarn spool having projecting axles to journal in said grooves beneath the plates, the yarn from the spool having free passage through the slot.

5 2. A knitting bag, as claimed in claim 1, in which one of said spool axles is tubular, and a jointed crank handle for turning the spool telescopically disposed in said tubular axle.

10

LEE BRUCE MOORE.
